(57) **CLAIM**

The ornamental design for a vacuum sealer, as shown and described.

DESCRIPTION

FIG. 1 is a front perspective view of a vacuum sealer showing my new design;

FIG. 2 is a top plan view thereof;

FIG. 3 is a top plan view thereof providing a call out region labeled by reference numeral 4; and,

FIG. 4 is an enlarged perspective view corresponding to the call out region identified by numeral 4 in FIG. 3.

The broken lines in FIGS. 3-4 are for reference purposes only and forms no part of the claimed design.
